[57] CLAIM

The ornamental design for a detachable base plate for a traffic sign, as shown and described.

DESCRIPTION

FIG. 1 is a top plan view of a detachable base plate for a traffic sign showing our new design;

FIG. 2 is a bottom plan view thereof;

FIG. 3 is a front elevational view thereof;

FIG. 4 is a rear elevational view thereof;

FIG. 5 is a right side elevational view thereof, with the opposite side being a mirror image;

FIG. 6 is a top plan view of a second embodiment thereof;

FIG. 7 is a bottom plan view thereof;

FIG. 8 is a front elevational view thereof;

FIG. 9 is a rear elevational view thereof; and,

FIG. 10 is a right side elevational view thereof, with the opposite side being a mirror image.
